CARBURETOR

Filed March 25, 1932

UNITED STATES PATENT OFFICE

JAMES WHYTE, OF LYNWOOD, CALIFORNIA

CARBURETOR

Application filed March 26, 1932. Serial No. 601,355.

This invention relates to a carburetor for internal combustion engines of the ignition type.

An object of my invention is to provide a carburetor in which relatively low gravity fuels may be used to operate the engine.

Another object is to provide a novel means whereby the fuel is fed into the carburetor under a slight pressure.

Still another object is to provide a carburetor of the character stated which can be adapted to either the up or down draft principle.

Other objects, advantages and features of invention may appear from the accompanying drawing, the subjoined detailed description and the appended claims.

In the drawing

Figure 1 is a side elevation of my carburetor as applied to an engine.

Figure 2 is a longitudinal, sectional view of the same.

Figure 3 is a side elevation of the needle valve.

Referring more particularly to the drawing, my carburetor 1 consists of a bowl 2 which includes a central air passage 3 in which a venturi 4 is provided. The venturi shoulders against the lower end of the bowl 2 and is held in position by a nut 5. An annular fuel chamber 6 surrounds the air passage 3 and fuel is fed to the chamber 6 through the pipe 7. The level of the fuel in the chamber 6 is controlled through a float 8 which actuates a needle valve 9 mounted at the juncture point of the pipe 7 and the chamber 6. The float 8 is connected to the needle valve 9 through the levers 10, and thus opens and closes the valve in the usual and well-known manner.

A plurality of fuel intake ports 11 extend from the chamber 6 through the venturi 4 and into the air passage 3. These ports are positioned adjacent the top of the venturi. As previously stated, the fuel in the chamber 6 is of relatively low gravity, and consequently, some pressure is required to force it through the ports 11 and into the air passage 3. I procure a pressure on the top of the fuel in the chamber 6 by means of ducts 12

which extend from the air passage 3 into the top of the chamber 6. A hood 13 projects downwardly over each of the ducts within the air passage 3, and the air traveling upwardly under a high velocity will be caught under these hoods and directed upwardly through the ducts 12 into the chamber 6, thus building up a pressure in the chamber to force the fuel out of the ports 11.

The fuel is heated in the chamber 6 by the hot exhaust gases from the engine, and these gases circulate around the chamber 6 in the annular hot air chamber 14. A pipe 15 rises from the bowl 2 and forms a continuation of the air passage 3. The pipe 15 extends into one end of the branch manifold 16. The pipe 15 is also surrounded by a heating chamber 17. The hot exhaust gases are conducted from the exhaust manifold 18 through a pipe 19, thence into a jacket 20 which surrounds one side of the branch manifold 16 and the gases then pass through ports 21, into the chambers 17 and 14. The cooled gases finally exhaust out of the ports 22.

When using low grade fuels the engine can not be started without the aid of a gasoline carburetor, and therefor, I have provided a gasoline carburetor 23 on the opposite side of the branch manifold 16 from the carburetor 1. The engine starts on gasoline and as soon as it is warmed the gasoline carburetor is shut off and the fuel oil carburetor is substituted.

Having described my invention, I claim:

1. A carburetor for low gravity fuels comprising a branch manifold adapted to be secured to the intake manifold of the engine, a gasoline carburetor on one end of said branch manifold, a low gravity fuel carburetor attached to the other end of the branch manifold, a jacket surrounding the branch manifold above the low gravity fuel carburetor, a pipe extending from the exhaust manifold of the engine to the jacket, a bowl, said bowl having a central air passage, a venturi in the air passage, a pipe extending from the bowl to the branch manifold, a heating chamber surrounding the pipe and the bowl in which the exhaust gases circulate, a fuel chamber surrounding the air passage, a fuel intake pipe extending into said fuel chamber, float

means in the fuel chamber, needle valve means connected to the float means, and means above the venturi in the air passage connected to the fuel chamber whereby pressure is exerted 5 on the top of the fuel, and a plurality of fuel ports extending into said air passage.

2. A carburetor for low gravity fuels comprising a branch manifold adapted to be secured to the intake manifold of the engine, a 10 gasoline carburetor on one end of said branch manifold, a low gravity fuel carburetor attached to the other end of the branch manifold, a jacket surrounding the branch manifold above the low gravity fuel carburetor, a 15 pipe extending from the exhaust manifold of

the engine to the jacket, a bowl, said bowl having a central air passage, a pipe extending from the bowl to the branch manifold, a heating chamber surrounding the pipe and the bowl in which the exhaust gases circulate, a fuel chamber surrounding the air passage, a fuel intake pipe extending into said fuel chamber, float means in the fuel chamber, needle valve means connected to the float means, and ducts extending from the air passage into the fuel chamber, a hood over each duct, and fuel ports extending from the fuel chamber into said air passage.

In testimony whereof, I affix my signature.

JAMES WHYTE.
